UNITED STATES PATENT OFFICE.

SIGMUND HOCHSTADTER, OF NEW YORK, N. Y.

DESIGN FOR A BOTTLE.

No. 37,956.

Specification for Design.

Patented April 17, 1906.

Application filed March 7, 1906. Serial No. 304,800. Term of patent 14 years.

To all whom it may concern:

Be it known that I, SIGMUND HOCHSTADTER, a citizen of the United States, residing at the city of New York, in the county and State of New York, have invented a new, original, and ornamental Design for a Bottle, of which the following is a specification, reference being had to the accompanying drawings, forming part thereof, and in which—incorporating my design, and Fig. 2 is a top view thereof.

I claim—

The ornamental design for a bottle, as shown.

SIGMUND HOCHSTADTER.
